UNITED STATES PATENT OFFICE.

JULIAN LAZOWSKI, OF NEW KENSINGTON, PENNSYLVANIA

RAIL FASTENER.

1,402,506.

Specification of Letters Patent.

Patented Jan. 3, 1922.

Application filed October 3, 1921. Serial No. 505,020.

To all whom it may concern:

Be it known that I, JULIAN LAZOWSKI, a citizen of Poland, residing at New Kensington, in the county of Westmoreland and State of Pennsylvania, have invented certain new and useful Improvements in Rail Fasteners, of which the following is a specification.

This invention relates to certain new and useful improvements in rail fasteners and has particular reference to a fastening device associated with a tie and rail supported thereon for anchoring the rail to the tie without the necessity of providing separable fish plates and fastening bolts for the rail.

The primary object of the invention resides in the provision of a rail fastener wherein rail engaging clamps and anchoring blocks are interlockingly associated with the tie supporting the rail and movable in directions at right angles to the clamp during interlocking engagement with the tie for anchoring the rail to the tie.

With the above general objects in view and others that will appear as the nature of the invention is better understood, the invention consists in the novel form, combination and arrangement of parts hereinafter more fully described in connection with the accompanying drawing and in which like characters of reference indicate corresponding parts throughout the several views.

In the drawing,

Figure 1 is a fragmentary side elevational view, partly in section of a rail tie constructed in accordance with the present invention having the rails mounted thereon,

Figure 2 is a fragmentary top plan view,

Figure 3 is a detail sectional view taken on line III—III of Figure 1 showing the rail engaging clamp retained in position by the anchoring block interlocked with the supporting tie,

Figure 4 is a fragmentary developed top plan view of a portion of the rail showing the manner of assembling the rail engaging clamp and anchoring the block on the tie,

Figure 5 is a perspective view of the rail engaging clamp showing the fish plate forming an integral part thereof and

Figure 6 is a perspective view of the anchoring block associated with the clamp.

Referring more in detail to the accompanying drawing, there is illustrated a tie supporting rails with means for anchoring the rails to the tie, the tie being constructed

of any suitable material and embodying a body portion 1 having a centrally positioned and longitudinally extending reinforcing rib 2 with a rail supporting block 3 positioned adjacent each end of the tie.

The tie block 3 projects upwardly of the tie as shown more clearly in Figures 1 to 3 and has a central cut away portion 4 constituting a transverse seat for the rail 5. The tie block 3 is adapted to receive a rail engaging clamp and anchoring block for the clamp, and to accommodate the clamp and anchoring block, the tie block 3, adjacent one side of the tie carries upstanding longitudinally extending walls 6 and transversely extending cross walls 7 terminating at points spaced from the opposite side of the tie as clearly shown in Figure 4 with the ends of the cross walls 7 beveled as at 8 for purposes presently to appear, the inner faces of the walls 6 and 7 being under cut at 9 and 10 respectively.

A rail engaging clamp is disposed at each side of the rail 5 as shown in Figure 1, the same embodying a body portion 11 having beveled side walls 12 and 12' and a beveled end wall 13, the forward end of the bottom face of the clamp being cut away as at 14 for engagement with the base flange of the rail, while the extreme forward end of the clamp carries a transverse integral fish plate 15. In mounting the clamp upon the tie for association with the rail, the same is positioned as illustrated in Figure 4, the clamp being moved transversely of the tie with the fish plate 15 engaging the webs of the rails with the cut away portion 14 overlying the base flanges, while the body portion 11 of the clamp is supported on the tie block 3 with the beveled end wall 13 engaging the under cut face 10 of the wall 7, while the beveled wall 12 engages the under cut face 9 of the wall 6, thereby interlocking the clamp with the tie.

An anchoring block is associated with the tie and rail engaging clamp and to accommodate the mounting of the anchoring block, the tie block 3, at the side opposite the wall 6 is provided with a longitudinally extending dove-tailed groove 16 opening at the end of the tie block, while the anchoring block 17 shown in detail in Figure 6 has a perpendicular outer wall 18 and a beveled inner wall 19, the bottom face of the anchoring block carrying a longitudinally extending dove-tail rib 20 while a beveled forward pro-

100

105

110

jection 21 is carried by the inner end of the anchoring block. In positioning the anchoring block for interlocking engagement with the tie, the same is placed as illustrated in 5 Figure 4, aligning the dove-tail rib 20 with the dove-tail groove 16 and moving the rib into said groove, the bevel face 19 of the anchoring block engaging the bevel wall 12' of the clamp with the projection 21 overlying the base flange of the rail. To retain the anchoring block in assembled position with respect to the tie, locking bolts 22 are passed through openings 23 in the anchoring block and threaded into the tie as shown in Figure 3.

The rails 5 supported on the tie seats have sockets in the bottom faces thereof adjacent the ends to receive pins 24 carried by the tie block 3 to prevent relative longitudinal movement of the rails. The easy manner in which the rail engaging clamp and anchoring block are moved into interlocking engagement with the tie is fully illustrated in Figure 4, the rail engaging clamp moving transversely of the tie while the anchoring block moves longitudinally thereof, the clamping block being interlocked with the tie and the clamping and anchoring blocks interlocked with each other.

30 While there is herein shown and described what is believed to be the preferred embodiment of the invention, it is nevertheless to be understood that minor changes may be made in the form, combination and arrangement of parts without departing from the spirit and scope of the invention as claimed.

35 What is claimed as new is:—

1. A rail fastener comprising in combination with a tie having a tie block adjacent 40 each end thereof, said block including upstanding longitudinal and transversely extending walls with the transverse walls terminating at points spaced from the adjacent side of the tie with the inner faces of the 45 walls under cut, a dove-tailed groove extending longitudinally of the tie block outwardly of the transverse walls and opening at the end of the tie block, a rail engaging clamp having beveled side and end walls supported on said tie block with one beveled side wall 50 and the end wall engaging the under cut faces of the tie block walls, an anchoring block having a dove-tailed rib received in said dove-tailed groove for anchoring the rail engaging clamp to the tie.

2. A rail fastener comprising in combination with a tie having a tie block adjacent each end thereof, said block including upstanding longitudinal and transversely extending walls with the transverse walls terminating at points spaced from the adjacent side of the tie with the inner faces of the 60 walls under cut, a dove-tailed groove extending longitudinally of the tie block outwardly of the transverse walls and opening at the end of the tie block, a rail engaging clamp having beveled side and end walls supported on said tie block with one beveled side wall 65

end of the tie block, a rail engaging clamp having beveled side and end walls supported on said tie block with one beveled side wall and the end wall engaging the under cut faces of the tie block walls and an anchoring 70 block having a dove-tailed rib and a beveled side wall with the rib received in the dove-tailed groove to position the beveled wall of the anchoring block for engagement with the outer beveled wall to the clamp.

3. A rail fastener comprising in combination with a tie having a tie block adjacent each end thereof, said block including upstanding longitudinal and transversely extending walls with the transverse walls terminating at points spaced from the adjacent side of the tie with the inner faces of the walls under cut, a dove-tailed groove extending longitudinally of the tie block outwardly of the transverse walls and opening at the 80 end of the tie block, a rail engaging clamp having beveled side and end walls supported on said tie block with one beveled side wall and the end wall engaging the under cut faces of the tie block walls, an anchoring 85 block having a dove-tailed rib and a beveled side wall with the rib received in the dove-tailed groove to position the beveled wall of the anchoring block for engagement with the outer beveled wall to the clamp, and 90 means for securing the anchoring block to the tie.

4. A rail fastener comprising in combination with a tie having a tie block adjacent each end thereof, said block including upstanding longitudinal and transversely extending walls with the transverse walls terminating at points spaced from the adjacent side of the tie with the inner faces of the walls under cut, a dove-tailed groove extending longitudinally of the tie block outwardly of the transverse walls and opening at the 100 end of the tie block, a rail engaging clamp having beveled side and end walls supported on said tie block with one beveled side wall and the end wall engaging the under cut faces of the tie block walls, an anchoring 105 block having a dove-tailed rib received in said dove-tailed groove for anchoring the rail engaging clamp to the tie, and a transversely extending integral rail engaging fish plate carried by the clamp.

5. A rail fastener comprising in combination with a tie having a tie block adjacent each end thereof, said block including upstanding longitudinal and transversely extending walls with the transverse walls terminating at points spaced from the adjacent side of the tie with the inner faces of the walls under cut, a dove-tailed groove extending 120 longitudinally of the tie block outwardly of the transverse walls and opening at the end of the tie block, a rail engaging clamp having beveled side and end walls supported on said tie block with one beveled side wall 125

and the end wall engaging the under cut faces of the tie block walls, an anchoring block having a dove-tailed rib and a beveled side wall with the rib received in the dove-tailed groove to position the beveled wall of the anchoring block for engagement with the outer beveled wall to the clamp, and a transversely extending integral rail engaging fish plate carried by the clamp.

10. 6. A rail fastener of the type described

comprising in combination with a tie having transverse and longitudinally extending grooved seats, a rail engaging clamp slidably mounted in the transverse seat and an anchoring block slidably mounted in the longitudinal seat engaging the clamp for locking the same to the tie. 15

In testimony whereof I affix my signature.

JULIAN LAZOWSKI.
